UNITED STATES PATENT OFFICE.

WALTER SHAFFER, OF DERBY, CONNECTICUT, ASSIGNOR TO WILBUR M. ALLING, OF SAME PLACE.

DESIGN FOR A KNITTING-MACHINE CAM.

SPECIFICATION forming part of Design No. 31,902, dated November 28, 1899.

Application filed October 30, 1899. Serial No. 735,324. Term of patent 7 years.

To all whom it may concern:

Be it known that I, WALTER SHAFFER, of Derby, in the county of New Haven and State of Connecticut, have invented and produced 5 a new Design for a Knitting-Machine Cam; and I do hereby declare the following, when taken in connection with the accompanying drawings and the letters of reference marked thereon, to be a full, clear, and exact description of the same, and which said drawings constitute part of this specification, and represent, in—

Figure 1, a view in side elevation of a knitting-machine cam containing my new design; 15 Fig. 2, a reverse side view thereof; Fig. 3, a top view thereof; Fig. 4, an edge view thereof; Fig. 5, a view thereof in central section.

As shown in the drawings, the leading or material feature of my design consists of three 20 broken or imperfect disks A, B, and C, having the same center and having their edges

grooved, as at a , b , and c . The disks A and B correspond to each other in form and are correspondingly located upon the opposite sides of the broken portion of the disk C, the 25 said broken portion of which is formed with three faces c' , c^2 , and c^3 , while the broken portion of the cam A is formed with two faces a' and a^2 and the broken portion of the cam B with two corresponding faces b' and b^2 . 30

Having fully described my invention, what I claim as new, and desire to secure by Letters Patent, is—

The design for a knitting-machine cam, as herein shown and described.

In testimony whereof I have signed this specification in the presence of two subscribing witnesses.

WALTER SHAFFER.
